(57) **CLAIM**

The ornamental design for an orthotic foot brace, as shown and described.

DESCRIPTION

FIG. 1 is an oblique view of an orthotic foot brace showing my new design;

FIG. 2 is a left side elevation view thereof;

FIG. 3 is a front elevation view thereof;

FIG. 4 is a top plan view thereof;

FIG. 5 is a rear elevation view thereof; and,

FIG. 6 is a bottom view thereof.

The broken lines are for the purpose of illustrating portions of an orthotic foot brace that form no part of the claim.
